[57] **CLAIM**

The ornamental design for dispensing valve for a beverage bottle incorporated in a head figurine wearing a baseball cap, as shown and described.

DESCRIPTION

FIG. 1 is a front view of the dispensing valve for a beverage bottle incorporated in a head figurine wearing a baseball cap showing our design;

FIG. 2 is a left side view thereof with the right side view being identical but reversed;

FIG. 3 is a rear view thereof;

FIG. 4 is a top view thereof; and,

FIG. 5 is a bottom view thereof.
